UNITED STATES PATENT OFFICE.

CRASSUS BUCHANAN, OF AUGUSTA, ARKANSAS.

TOBACCO-CARTRIDGE.

1,234,279.

Specification of Letters Patent. Patented July 24, 1917.

Application filed November 18, 1916. Serial No. 131,125.

To all whom it may concern:

Be it known that I, CRASSUS BUCHANAN, a citizen of the United States, residing at Augusta, in the county of Woodruff and 5 State of Arkansas, have invented certain new and useful Improvements in Tobacco-Cartridges; and I do declare the following to be a full, clear, and exact description of the invention, such as will enable others 10 skilled in the art to which it appertains to make and use the same.

This invention relates to improvements in cartridges or charges of tobacco.

One object of the invention is to package 15 or incase tobacco in convenient form for chewing, whereby a great economy to consumers is effected and absolute cleanliness insured.

Another object is to provide individual 20 chewing charges in cartridge form which will retain their original form and physical characteristics for a considerable time, and which prevents crumbs of tobacco from being scattered about and from lodging between 25 the teeth and in cavities in the mouth of the user.

Another object is to provide individual 30 charges of chewing tobacco inclosed in casings which are non-disintegrating when subjected to moisture, permitting the juice to pass out and the solid particles to be retained.

With these and other objects in view, the invention consists of certain novel features 35 of construction, and the combination and arrangement of parts which will be herein-after fully described and claimed.

In the accompanying drawings:

Figure 1 represents a perspective view of 40 a cartridge constructed in accordance with this invention;

Fig. 2 is a longitudinal section thereof; and

Fig. 3 is a transverse section.

It is known that it is not broadly new to provide separate charges or cartridges of tobacco for chewing purposes, but these charges, so far as I am aware, have either been incased in tobacco leaves or in material 50 which disintegrates when subjected to moisture.

In the embodiment illustrated, a cartridge 1 is shown composed of a tobacco filler 2 which may be in any desired form, either 55 whole pieces, fine cut, or crushed, inclosed in a casing 3 composed of material which is

non-disintegrating when subjected to moisture, textile fabric being preferably employed for this purpose. This fabric is preferably made in the form of tubes and 60 cut transversely into sections to form the individual casings 3. These casings are closed at both ends to securely retain the tobacco placed therein, stitching being preferably used to effect these closures. It is 65 essential that these casings be porous in nature and also sufficiently strong to withstand the grinding produced by chewing, and linen fabric is especially desirable for this purpose as it is absolutely tasteless and 70 very strong, linen thread being used for closing the ends of the casings.

Many advantages are derived from the use of these cartridges, among which is the promotion of economy to consumers, as tobacco 75 put up in this form is not liable to accumulate tobacco dust in the pocket or box and it also obviates the necessity of pinching off or biting off pieces, a part of which either falls to the ground or upon the face or clothing of the user.

This form of using tobacco is also especially desirable for snuff dippers which habit is prevalent among women in the South and West. These packages prevent the particles 85 of snuff from flying about and also from entering the lungs which frequently occurs when employed in the ordinary manner. This form of cartridge also prevents particles of tobacco from lodging between the 90 teeth and in the cavities of the user's mouth.

These individual cartridges may be put up in any desired containers, the size of which of course will be controlled by the number of individual cartridges it is desired to place in each container and the cartridges may be marketed either in individual form or otherwise.

It is of course to be understood that these cartridges may be made of any desired size 100 according to the quantity of tobacco to be incased, and larger and smaller cartridges may be packed and sold in the same container for use by consumers requiring larger or smaller chews, or a plurality of large 105 pieces may be placed in one package and smaller pieces in another, so that consumers may have their choice.

I claim:

A quid of tobacco of a size to be received 110 in the mouth and chewed, and comprising a tobacco filling and a casing of tubular fab-

ric, the ends being closed by stitches, the fabric being of a texture to be permeable to the tobacco juice and sufficiently tough to be resistant to the cutting action of the teeth and non-disintegrating under the action of the saliva.

In testimony whereof I have hereunto set

my hand in the presence of two subscribing witnesses.

CRASSUS BUCHANAN.

Witnesses:

A. H. HAMILTON,

I. J. STACY.
